FIG. 1

FIG. 2

To all whom it may concern:

Be it known that we, Anthony De Bernardi and Mario Palombi, citizens of the United States of America residing, respectively, at Brighton, Massachusetts, and Hyde Park, Massachusetts, have invented a new, original, and ornamental Design for a Cup, of which the following is a specification, reference being had to the accompanying drawing, forming a part hereof.

Fig. 1 is a perspective view of a cup, showing our new design; and

Fig. 2 is another perspective view thereof.

As is shown by the drawing, the portion of the design on the inner surface of the cup comprises four similar floral-bouquet motifs alternating with four identical ribbon motifs.

We claim:

The ornamental design for a cup, as shown and described.
